FLEXIBLE SPINNING TOY

Donald E. Snyder, P.O. Box 478, Colona, Ill. 61241

Filed Oct. 1, 1973, Ser. No. 402,629

Term of patent 14 years

Int. Cl. D21—01

U.S. Cl. D34—15 W

FIG. 1 is a top plan view of a flexible spinning toy embodying my new design;

FIG. 2 is a bottom plan view thereof; and

FIG. 3 is an edge elevational view thereof shown on an enlarged scale partially in section.

I claim:

The ornamental design for a flexible spinning toy, as shown and described.
